UNITED STATES PATENT OFFICE.

JOHN A. HOLFELDER, OF UNIONTOWN, PENNSYLVANIA, ASSIGNOR TO McCRUM-HOWELL COMPANY, OF NORWICH, CONNECTICUT, A CORPORATION OF CONNECTICUT.

DESIGN FOR A WALL-RADIATOR SECTION.

No. 39,031.

Specification for Design.

Patented Jan. 21, 1908.

Application filed November 2, 1907, Serial No. 400,419. Term of patent 14 years.

To all whom it may concern:

Be it known that I, JOHN A. HOLFELDER, a citizen of the United States, residing at Uniontown, county of Fayette, and State of Pennsylvania, have invented a new, original, and ornamental Design for a Wall-Radiator Section, of which the following is a specification, reference being had to the accompanying drawing, forming part thereof.

In the drawing, Figure 1 is a side view of

the radiator section showing my new design; Fig. 2 is an end view.

I claim:

The ornamental design for a wall radiator section, as shown.

JOHN A. HOLFELDER.

In presence of—

W. M. MACKAY,
J. W. CURTIS.
